TUFTING MACHINE

Joseph W. Droll, Chicago, Ill., assignor to J. W. Droll Company, Chicago, Ill., a corporation of Delaware

Application September 13, 1937, Serial No. 163,573

8 Claims. (Cl. 45—138)

The invention relates to tufting machines of the type in which a pair of compressor-frames are mounted to swing vertically for convenience of the operator in sewing or tying the tufts in the mattress.

The object of the invention is to provide a mattress-tufter of this type in which both of the frames are shifted simultaneously and equidistantly from the axis around which they swing so that in varying the spacing between them to compress or release a mattress the balanced relation of the frames with respect to the axis will be maintained. This makes it possible to maintain the balance of the structure so it will swing easily when mattresses of different thicknesses are compressed.

Other objects of the invention will appear from the detail description.

The invention consists in the several novel features which are hereinafter set forth and more particularly defined by claims at the conclusion hereof.

In the drawings: Fig. 1 is a plan of a machine embodying the invention. Fig. 2 is a central longitudinal section on line 2—2 of Fig. 1. Fig. 3 is a section through the coupling-sleeve for driving the gearing for shifting the frame, in their operative position. Fig. 4 is a section on line 4—4 of Fig. 2, the frames being shown in position for compressing a mattress. Fig. 5 is a similar view illustrating the frames in position to receive the mattress. Fig. 6 is a perspective of the power-mechanism for driving the gearing for shifting the compressor-frames. Fig. 7 is a section on line 7—7 of Fig. 1 showing the mechanism for automatically stopping said gearing within predetermined limits. Fig. 8 is a section on line 8—8 of Fig. 2.

The invention is exemplified with a machine comprising a rigidly connected base 10 and standards 11 and 12 which constitute a supporting frame; a pair of frames 15 and 16 between the standards. Each frame carries a series of compressor-members 28 having tapered sides and slots 29 having holes 30 through which the tufting needles can be passed to draw the ties through the mattress at the points where the tufts are to be secured on the mattress. Each compressor-member is adapted to compress the mattress along a line for a complete longitudinal row of tufts. Each frame 15, 16 comprises rigidly connected side-bars 18 and end-bars 19. The compressor-members 28, if desired, are adjustably connected to the frames 15, 16, respectively to adapt the machine for different transverse spac-

ings between the tufts, as set forth in Patent No. 1,949,148 and the connections shown are substantially the same as in said patent. The frames 15 and 16 and compressor-members are pivotally sustained to rotate vertically from a horizontal position for receiving a mattress to be tufted to a vertical position for convenience of the operator in passing the tufting needles and ties horizontally through the compressed mattress. The frames and compressor-members thereon are movable from each other to provide sufficient space between them to permit an untufted mattress to be easily placed on the compressor-members of the frame 16 and the tufted mattress to be removed therefrom, and also to compress the mattress at the places to be tufted. Heretofore in machines of this type, one of the frames was pivotally supported for vertical rotation, and the other frame was supported by and movable to and from the other. In this manner of supporting the frames for vertical swinging, the relative movement between the frames for receiving and compressing the mattress the distance between the axis of the pivot and one frame was fixed and the other varied. In consequence, the swinging structure was not kept in balance for easy rotation. The invention provides a machine in which the frames are rotatable together and are equidistantly and simultaneously adjusted to and from the axis on which the frames swing, so that the frames will counterbalance each other when they are in mattress-receiving and in mattress-compressing positions.

The rotatable structure comprises a longitudinally aligned pair of parallel supporting members 20, 21 at the ends of the frames 15 and 16, respectively. Members 20, 21 are provided with coaxial trunnions 20^a, 21^a which are journalled in the standards 11 and 12. The frame 15 is slidably supported at each end on a pair of shafts 22 which are journalled, and held against longitudinal movement in the members 20, 21. The frame 16 is slidably supported, at each end, on shafts 22. Shafts 22 are provided with right-hand screw-threads 24 which engage nuts 25 which are fixed to frame 15 to shift said frame to or from members 20, 21 and with left-hand screw-threads which engage nuts 26 which are fixed to frame 16. Rotation of shafts 22 in members 20 will, through the screw-threads and nuts 24, shift the frames rectilinearly, simultaneously and equidistantly to or from the members 20, 21 and the axis of trunnions 20^a, 21^a. All of the shafts 22 are connected for simultaneous rotation by a sprocket-chain 31 and sprockets 32 fixed

to the shafts 22, respectively. Sprockets 32 are confined in brackets 33 which are fixed to and project below frame 16, so as to move vertically with said frame and are splined to shafts 22 to drive the sprockets in all positions of frame 16 on said shafts. Thrust-bearings 22^a are provided between shafts 22 and frames 20, 21. Pairs of links 70 are pivoted to frames 15, 16 and to one another inwardly of the shafts 22 to confine the mattress against contact with the structures at the ends of frames 15, 16. Tubular sleeves 71 enclose the upper and lower ends of shafts 22. Sprockets 72 are adjustably secured to frame 16 for tightening the sprocket-chain 31. One of the shafts 22 is adapted to be driven by a bevel-gear 34 which is fixed to said shaft within brackets 35, 36 which are fixed to, and form a part of, trunnion-member 20. A bevel-gear 40 meshes with gear 34 and is fixed to a horizontal shaft 41 which is journaled in bracket 36 and has an outwardly extending end provided with a polygonal end which is adapted to be driven from a coupling-sleeve 42 which is separable from shaft 41 to permit the frames 15 and 16 to be rotated on the transmission-axis.

Shaft 41 for driving the shafts 22 for shifting the compressor-members and frames 15, 16 relatively to each other, is operable by power from an electric motor 44 through mechanism which comprises a shaft 45 on which coupling-sleeve 42 is slidably mounted. Shaft 45 is journaled in standard 12 and is driven from a countershaft 46 by a sprocket wheel 47 fixed on shaft 46, chain 48, and a sprocket 49 fixed to shaft 45. Shaft 41 is coaxially disposed with respect to the trunnions and is adapted to move into coaxial alignment with shaft 45 when the frames 15, 16 are swung into horizontal position. During the swinging of the frames shaft 41 passes out of alignment with shaft 45. When shafts 45, 41 are in axial alignment, coupling-sleeve 42 can be slidably shifted on shaft 45 by means of a lever 42^a to couple the shafts so that shaft 41 which is carried by the trunnion-member 20 will be driven from shaft 45. Screws 70^a are adapted to engage trunnions 20^a, 21^a to lock the frames 15, 16 in horizontal or vertical positions. Pulleys 47^a and 48^a are loose on shaft 46 and a pulley 49^a is fixed to said shaft. A pulley 50 is fixed to the shaft of motor 44. A belt 51 around pulleys 47^a, 50 is movable onto pulley 49^a to drive shaft 46 in one direction. A crossed belt 52 around pulleys 48^a, 50 is movable onto pulley 49^a to drive shaft 46 in the reverse direction. A hand-lever 52^a fulcrumed on a support 53 which is fixed to standard 12 is adapted to shift belt 51 to drive pulley 49^a. A hand-lever 54 fulcrumed on support 53 is adapted to shift belt 51 to drive pulley 49^a. A latch-bar 55 is pivoted at 56 on lever 52^a to swing vertically, is retractible by a spring 57, and has ratchet-notches 58 whereby it may be locked to a fixed bar 59 in two positions, one to hold lever 52 in position to hold belt 51 on loose pulley 47 and the other to hold said belt on pulley 49^a. A latch-bar 60 is pivoted on lever 54 to swing vertically, is retractible by a spring 61, and is provided with notches 62 for engaging a fixed bar 63 to lock lever 54 in position to hold belt 52 on pulley 48^a or pulley 49^a. An abutment 64 is connected to a hanger-bar 65 which is fixed to frame 15, and is adapted to automatically trip latch-bar 55 when frames 15, 16 have been separated the desired distance to receive a mattress. An abutment 66 is connected to bar 65 and is adapted to trip latch-bar 60 when frames 75

15, 16 have been shifted into mattress-compressing position. These abutments are connected to bar 65 by bolts and slots so either may be adjusted to trip the latch-bars at different high or low limits for mattresses of different thicknesses.

The operation will be as follows: When the frames 15, 16 are locked in horizontal position by screws 70^a and spread apart, as shown in Fig. 5, the operator will place the mattress to be tufted on the lower frame 16. Shafts 41 and 45 will then be coaxial. Lever 42^a will then be operated to slide coupling-sleeve 42 partly onto shaft 41 and connect it to the power-operated gearing. The operator will then shift lever 52^a to move the constantly driven belt 51 onto pulley 49, whereupon shaft 45 will be driven from shaft 46 through sprockets 47, 49 and chain 48. Latch-bar 55 will lock lever 52^a in its operative position. Shaft 41 will be driven by sleeve 42, and will drive bevel-gears 40, 34 and the screw-shaft 20 to which gear 34 is fixed. The other shafts 20 will be simultaneously driven by chain 31 and sprockets 32. The screws on shaft 20 will shift the frames 15 and 16, simultaneously and equidistantly toward each other and the axis of trunnions 20^a, 21^a. When the compressor-members have compressed the mattress to the desired point, abutment 64 will trip latch-bar 55 and spring 57 will retract hand-lever 52^a to move belt 51 off pulley 49^a. This will automatically stop the movement of the frames 15, 16. Next the operator will shift lever 42^a to uncouple sleeve 42 from shaft 41. Screws 70^a will then be released by the operator. The frames 15 and 16 and trunnion-members 20^a, 21^a with a compressed mattress can then be swung into vertical position for tufting. After the mattress has been tufted, the frames 15, 16 with the tufted mattress and members 20, 21 will be swung back to horizontal position and coupling-sleeve 42 will be slipped onto shaft 41. Lever 54 will then be shifted to move belt 52 onto pulley 49^a to drive the pulley in the reverse direction. The screw-shafts 22 will then be rotated to move the frames 15, 16 and the compressor-members equidistantly from the trunnion axis so the tufted mattress can be removed. When the frames are separated the desired distance for this purpose, abutment 66 will strike and trip latch-bar 65 to release lever 54. Spring 61 will retract lever 54 to move belt 52 onto the loose-pulley 48^a and automatically stop the gearing for operating screw-shafts 22.

An important attribute of the machine is that the upper and lower frames and compressor-members are always shifted in opposite directions simultaneously and equidistantly toward or away from the axis of the trunnions 20^a, 21^a, and in consequence they counter-balance each other in all spacings and when spaced to compress mattresses of different thicknesses.

The invention is not to be understood as restricted to the details set forth, since these may be modified within the scope of the appended claims, without departing from the spirit and scope of the invention.

Having thus described the invention, what I claim as new and desire to secure by Letters Patent is:

1. In a tufting machine, the combination of a pair of frames each provided with elements for compressing a mattress at the places to be tufted, a pair of supports at the ends of the frames, coaxial trunnions mounted on said supports for pivotally supporting the frames to swing vertically, a plurality of screws on each of the sup-

ports on which each of the frames is supported for rectilinear movement relatively to the axis of the trunnions, and mechanism for simultaneously operating all the screws for shifting the frames equidistantly relatively to the axis of the trunnions for compressing or releasing a mattress so that the frames will be equidistantly spaced from said axis while they are in compressing position for mattresses of different thicknesses.

2. In a tufting machine the combination of a pair of end-supports pivotally supported to swing vertically on a substantially horizontal axis, a pair of substantially parallel frames adapted to support an entire mattress between the supports and provided with elements for compressing the mattress for tufting, devices at the ends of the frames, respectively, between the supports and the frames for supporting the frames for rotation with the supports and for rectilinear movement to and from the axis of said supports, and means for simultaneously operating said devices to equidistantly shift said frames in parallelism and to and from the axis so that the frames will remain parallel and be equidistantly spaced from said axis while mattresses of different thicknesses are compressed between them.

3. In a tufting machine the combination of a pair of end-supports pivotally supported to swing vertically on a substantially horizontal axis, a pair of substantially parallel frames adapted to support an entire mattress between the supports and provided with elements for compressing the mattress for tufting, a plurality of devices at the ends of the frames, respectively, between the supports and the frames for supporting the frames for rotation with the supports and for rectilinear movement to and from the axis of said supports, and means for simultaneously operating said devices to equidistantly shift said frames in parallelism and to and from the axis, so that the frames will remain parallel and be equidistantly spaced from said axis while mattresses of different thicknesses are compressed between them.

4. In a tufting machine the combination of a pair of end-supports pivotally supported to swing vertically on a substantially horizontal axis, a pair of substantially parallel frames adapted to support an entire mattress between the supports and provided with elements for compressing the mattress for tufting, devices comprising screws at the ends of the frames, respectively, between the supports and the frames for supporting the frames for rotation with the supports and for rectilinear movement to and from the axis of said supports, and means for simultaneously operating said screws to equidistantly shift said frames in parallelism and to and from the axis so that the frames will remain parallel and be equidistantly spaced from said axis while mattresses of different thicknesses are compressed between them.

5. In a tufting machine the combination of a pair of end-supports pivotally supported to swing vertically on a substantially horizontal axis, a pair of substantially parallel frames adapted to support an entire mattress between the supports and provided with elements for compressing the mattress for tufting, devices at the ends of the frames, respectively, between the supports and the frames for supporting the frames for rotation with the supports and for rectilinear movement to and from said axis, power operable mechanism for simultaneously operating said devices

to equidistantly shift said frames in parallelism and to and from the axis so that the frames will remain parallel and be equidistantly spaced from said axis while mattresses of different thicknesses are compressed between them, and means for automatically stopping said mechanism to stop the frames at different equidistant predetermined positions from the axis in the spreading and closing movements of the frames.

10 6. In a tufting machine the combination of a pair of end-supports pivotally supported to swing vertically on a substantially horizontal axis, a pair of substantially parallel frames adapted to support an entire mattress between the supports and provided with elements for compressing the mattress for tufting, screws at the ends of the frames, respectively, between the supports and the frames for supporting the frames for rotation with the supports and for rectilinear movement to and from said axis, power operable mechanism for simultaneously rotating said screws to equidistantly shift said frames in parallelism and to and from the axis so that the frames will remain parallel and be equidistantly spaced from said axis while mattresses of different thicknesses are compressed between them, and means for automatically stopping said mechanism to stop both frames at different equidistant predetermined positions from the axis in the spreading and closing movements of the frames.

30 7. A mattress tufting machine comprising a pair of mattress compressing frames, means at opposite ends of the frames spacing and supporting said frames in opposed substantially parallel relationship comprising parallel screws with oppositely directed threads at their opposite ends threadedly connecting with the frames at opposite ends of said frames whereby the frames will move toward and away from each other upon simultaneously rotating said screws, driving means positioned in a plane disposed between said frames for simultaneously rotating said screws upon actuation of said driving means to cause the frames to simultaneously move toward and away from each other, and means revolvably supporting said frames at their opposite ends for revolving the frames in a path of travel common to both frames at any degree of spacing of the frames and means for actuating said driving means.

40 8. A mattress tufting machine comprising a pair of spaced, opposed, substantially parallel frames adapted to receive a mattress therebetween, means at opposite ends of the frames connecting between said ends and supporting said frames for simultaneous movement thereof toward and away from each other, cooperatively connected driving and driven means connected with said frames and positioned in a plane disposed between said frames for causing said movement upon actuation of said driving means, means for actuating said driving means, means providing a supporting axis for the frames at opposite sides of which the frames are substantially equidistantly related at any position of the frames during said movement so that the weight of one frame will counterbalance the weight of the other frame to enable the frames to be sustained in an inclined position upon revolving about said axis, means revolvably mounting said frames for revolving about said axis.

JOSEPH W. DROLL.
